UNITED STATES PATENT OFFICE.

THOMAS A. GALT, OF RIVER FOREST, ILLINOIS, ASSIGNOR TO THE ADLAKE COMPANY,
A CORPORATION OF ILLINOIS.

DOME LIGHT.

Application filed January 14, 1927. Serial No. 161,119.

This invention relates to illuminating devices and more particularly to shields and the like for screening or cutting off certain rays of light in lamps and the like.

5 The principal object of the invention is the provision of new and improved means in lamps and the like for screening or cutting off certain of the laterally directed rays of light, together with a new and improved manner of mounting the same within the lamp.

Other objects of the invention are the provision of a new and improved light shield that is simple in construction, cheap to 15 manufacture, unobtrusive to the sight, efficient in use, and that is not likely to become broken or detached.

Other and further objects and advantages of the invention will appear from the following description taken in connection with the accompanying drawings, in which

Fig. 1 is a side elevation of a bus or vehicle with parts in section and parts broken away;

25 Fig. 2 is a vertical section of the lamp showing the invention in position therein;

Fig. 3 is a bottom plan view of the same with the dome and its support removed and with the hinge shown in section;

30 Fig. 4 is a section on line 4—4 of Fig. 3; and

Fig. 5 is a view similar to Fig. 4 but showing a modified form of the device.

In illuminating busses and the like the 35 lamps or electric lights are usually mounted on the ceiling or under surface of the roof of the car. But in this position the light rays are confusing to the driver for the reason that the light about him being stronger than the light exterior of the vehicle he is more or less blinded by the light within the car. The rays from the lamps within the car are often reflected from the windshield or side windows, thus interfering seriously 40 with the driver's vision and therefore often interfering with the proper control of the car.

It has been proposed in some cases to provide screens exterior of the lamp, and in 50 others to paint the globe of the lamp in order to intercept the rays directed toward the shield, but all such devices are unsightly and more or less cumbersome and impractical. The present invention contemplates 55 the use of a shield that is mounted within

the lamp globe on the reflector in such a position that it is not visible when the globe or bowl is in position.

The invention is especially adapted to be used in connection with illuminating devices 60 for busses and the like, and by way of example is thus disclosed. On the drawings the reference character 10 designates a bus having the body 11 and the seat 12. The body 11 is provided with a top wall 13 and with a windshield 14 at its forward end, as is usual in such constructions. A chauffeur's seat is mounted in the front end of the body 11 in the usual manner.

A plurality of lamps or lights 15 are 70 mounted on the underside of the top wall or deck of the body 11. These illuminating devices may be of any suitable form or construction. In the form disclosed, which is by way of example only, each lamp comprises a base or bulb support 17 having the ring portion 18 which is adapted to be attached to the top or deck of the bus. The inner portion of the support is shaped to form a reflector 19 carrying the bulb 21. 75 The lamp is provided with a globe or dome 22 which is provided with a lateral flange 23 on the free edge of its side wall for engaging an inwardly extending ledge 24 on the dome support 25. The flange 23 is 80 held in position by a spring ring 26 engaging in a recess 27 in the dome support 25. The support 25 is hinged to the bulb support 17 as at 28 and its opposite end is secured in position by the screw 29.

It is desirable that none of the rays of light from the lamps 15 be permitted to strike the windshield 14 or the windows at each side of the driver's seat. A screen is provided for intercepting the rays directed toward the front of the vehicle. In the form of the device selected to illustrate one embodiment of the invention a screen 31 is employed for this purpose. The screen is in the form of a curved band rigidly attached as by means of rivets 33 to the shoulder 32 which extends about the reflector 19. It is of sufficient width to extend adjacent to the bottom of the dome 22. When the lamp is installed the screen is turned toward the front so that it will intercept rays of light that would otherwise strike the windshield and windows at the sides of the driver, as indicated in Fig. 1.

The form of the device shown in Fig. 5 110

differs from that just described in that the screen 310 is cast integral with the shoulder 320 of the base or bulb supporting member 170.

5. In all forms of the device the shield is mounted within the housing formed by the lens and dome.

It is thought from the foregoing taken in connection with the accompanying drawings that the construction and operation of my device will be apparent to those skilled in the art, and that various changes in size, shape, proportion and details of construction may be made without departing from the 15 spirit and scope of the appended claims.

I claim as my invention:

1. In a dome light for vehicles, a supporting member, a source of light carried by said member, a screen extending about one 20 side of said source of light, and a dome for enclosing said screen, said dome having its attaching edge in engagement with said screen.

2. In a dome light for vehicles a base 25 plate having its central portion shaped to form a reflector with a circular shoulder extending about the same, a source of light carried by said plate, and a curved screen rigidly attached to said shoulder for intercepting rays of light from said source.

3. In combination, a vehicle provided with

a body, a driver's seat in the front of said body, a lamp secured to the ceiling of said body, said lamp comprising a base, a light bulb carried by said base, and a screen carried by said base for intercepting only the rays of light from said bulb projected forwardly above said seat, and a diaphanous dome carried by said base and enclosing said bulb and screen. 35

4. In a dome light, a support, said support being shaped to form a reflector with a shoulder extending about said reflector, a bulb carried by said support, a curved screen member, and means for rigidly securing 45 said screen to said shoulder. 40

5. In a dome light for vehicles, a base member, a light bulb carried by said member, a light intercepting screen member secured to said base member adjacent to the 50 periphery thereof and extending partially around said bulb, and a dome for enclosing said screen and bulb, and means hinged to said base for supporting said dome.

6. In a dome light, a base, an electric 55 light bulb secured to said base, a light intercepting screen integral with said base and adapted to extend partially around said bulb, and a dome for enclosing said bulb and screen. 60

In testimony whereof I affix my signature.

THOMAS A. GALT.
